his ATTORNEY.

UNITED STATES PATENT OFFICE.

THOMAS J. SWEENEY, OF CLEVELAND, OHIO, ASSIGNOR TO JOHN V. KENNEDY AND ADOLPH S. DEUTSCH, OF CLEVELAND, OHIO.

INJECTOR FOR STEAM-BOILERS.

SPECIFICATION forming part of Letters Patent No. 757,849, dated April 19, 1904.

Application filed June 8, 1903. Serial No. 160,571. (No model.)

To all whom it may concern:

Be it known that I, THOMAS J. SWEENEY, a citizen of the United States, residing at Cleveland, in the county of Cuyahoga and State of Ohio, have invented certain new and useful Improvements in Injectors for Steam-Boilers; and I do hereby declare the following to be a full, clear, and exact description of the invention, such as will enable others skilled in the art to which it pertains to make and use the same.

My invention relates to injectors for steam-boilers, the object being to construct an injector which provides means for introducing cold water directly from the water connection to the cold - water chamber or condensing-chamber of the injector at will when the temperature in this chamber has been increased and thus renders the injector inoperative.

Another object of my invention is the arrangement of valves and chambers in such a manner as to obtain the best results and render the injector completely under control at all times.

My invention consists, broadly, in providing a valve-controlled cold-water branch connecting or communicating at one portion with the cold-water inlet and at the other portion with the cold-water overflow-chamber.

My invention further consists in the arrangement of valves for controlling the cold-water inlet and branch whereby both are controlled from a single stem according to predetermined adjustment.

My invention further consists in other constructive features and combination of parts, all of which will be hereinafter fully set forth, and particularly pointed out in the claims.

In the drawings, Figure I is a longitudinal vertical sectional view illustrating the interior arrangement of an injector constructed according to my invention and showing the same with the valves of the cold - water inlet and the branch both open. Fig. II is a longitudinal sectional view similar to Fig. I, illustrating the cold-water inlet and branch valves closed. Fig. III is a sectional view and a plan view illustrating the puppet-valve spring controlled and seat of same for controlling the opening leading to the cold-water branch.

A represents the barrel or casing of an injector, which has the usual threaded extension B, C, and D for the steam, water, and boiler delivery connections, respectively. The barrel A is divided into steam-chamber E, suction or water chamber F, cold-water overflow-chamber G, and hot - water overflow - chamber H, the hot-water overflow-chamber H being provided with a valve J, which in turn is provided with a stem J', extending through the cap J². The object of extending the stem J' through the cap is to provide means for determining from the exterior the action of the injector. A small locking jack or lever K is preferably provided for locking the valve J to its seat, which is desirable under certain conditions. The valve J controls communication between the hot - water overflow - chamber H and an overflow-pipe H', which communicates with the chamber H when the valve is open through the valve-opening and an annular chamber h, surrounding the barrel A at this point. The usual steam tube or nozzle f, lifting tube or nozzle g, and condensing or delivery tube or nozzle j are provided and properly arranged, as illustrated, and the discharging-mouth of the delivery tube or nozzle is provided with a valve-seat j', which when the injector is not in operation is automatically closed by a valve k to prevent backflow through the injector. The valve k is mounted and guided within a spider-arm k' in a similar manner to that of the valve illustrated in Fig. III of the drawings, thus leaving the delivery end of the injector open with the exception of this slight obstruction. The condensing or delivery tube or nozzle j is provided with openings j² and j³, leading, respectively, into the hot-water overflow-chamber H.

M represents the branch conduit, which leads at its lower end through valve-controlled orifice m into the suction-chamber F and from thence communicates through a valve-controlled orifice with the cold-water inlet-supply C. At the upper end branch conduit M communicates with the cold-water overflow G. A puppet-valve N, spring-controlled and opening inward toward the branch M, is located at the bottom of the conduit M, controlling the

passage-way between said branch conduit and the suction-chamber F and cold-water supply C. This valve N closes under normal conditions or working conditions of the injector 5 and opens when cold water is supplied to the branch M.

A valve O, which is mounted upon a stem O', controls the opening *m* for the admission or cut off of cold water. Mounted on the 10 valve-stem O' is another valve, which controls the orifice *p*, communicating between the water-supply C and suction-chamber F. The valves O and P are so disposed upon the stem O' that the valve P may be opened considerably 15 in advance of the valve O, and thus cold water be supplied through inlet C to suction-chamber F and cut off from cold-water overflow branch M. The further opening of the valve, however, as illustrated in Fig. I, allows 20 the cold water to pass into branch M and thence into cold-water overflow G, cooling the water if the same should become overheated through insufficient supply of cold water or oversupply of steam or too high pressure of steam. It is this feature that distinguishes 25 my injector from other injectors, as cold water can be immediately and directly supplied to the cold-water chamber G when the injector becomes inactive, as above set forth, and it is thus that I attain quick and positive action 30 and control of the injector.

The operation of the injector is as follows: The connection B is caused to communicate with the steam-chamber of the boiler. The 35 connection C communicates with the water-supply. The connection D communicates with the boiler at or below the water-level, and the connection H is an overflow or escape. Steam being supplied to the chamber E and the valve 40 A' being opened, the steam passes through the steam tube or nozzle *f*, which, being inserted within the lifting tube, or nozzle *g*, tends to lift the water into the suction-chamber F, steam thence passing along through the different tubes of the injector until the air on the inside of the injector has been expelled 45 and a vacuum secured inside of the working barrel, during which operation the valve J may be opened, or, as a matter of fact, opens of itself. After the vacuum is secured, however, the valve J automatically closes and, if desired, may be locked to its seat with the locking lever or jack K; but this is not absolutely essential if the valve J is air-tight and 50 self-seating.

It is to be understood, of course, that during the above operation the valve P is opened and the valve D closed. If the water in the chamber G should become overheated to such an extent as to render the injector inaccurate 60 or destroy the vacuum or the steam not be condensed, thus stopping the flow of water into the water-chamber of the boiler, the valve O is opened, as illustrated in Fig. I, and cold water supplied to the chamber G directly 65 through the branch M until the injector again begins to act, when the valve N will automatically close.

What I claim is—

1. In an injector, the combination with the 70 main water-inlet, of a branch communicating therewith at one end, and communicating with the cold-water overflow-chamber, at its other end.

2. A steam-injector, comprising a suction-chamber, steam-chamber, cold and hot water overflow-chambers, and valves for controlling the same, with a main cold-water supply, and separate branch cold-water supply, both valve-controlled, said branch cold - water supply 75 communicating with the main cold-water supply, and with the cold-water overflow-chamber, substantially as and for the purpose set forth.

3. In a steam-injector the combination with 80 the cold-water supply-chamber, of a branch communicating with said cold-water supply-chamber, said branch being provided with a valve adapted to automatically open inward toward said branch, and a cold-water overflow-chamber with which said branch communicates, substantially as and for the purpose set forth.

4. A steam-injector comprising steam, suction, cold and hot water overflow-chamber, 95 with suitable suction-tubes leading from one to the other of these chambers, a valve located in the hot-water overflow-chamber, opening outwardly and provided with means extending through the indicator for indicating its 100 position, with means for locking said valve to its seat, substantially as set forth.

Signed at Cleveland, in the county of Cuyahoga and State of Ohio, this 17th day of December, 1902.

THOMAS J. SWEENEY.
